(57) **CLAIM**

The ornamental design for a container sleeve, as shown and described.

DESCRIPTION

FIG. 1 is a front elevation view of a container sleeve positioned about a container showing my new design;

FIG. 2 is a front perspective view of the container sleeve showing my new design;

FIG. 3 is a top plan view of the container sleeve showing my new design;

FIG. 4 is a left side view of the container sleeve showing my new design;

FIG. 5 is a right side view of the container sleeve showing my new design;

FIG. 6 is a front view of the container sleeve showing my new design.

FIG. 7 is a rear view of the container sleeve showing my new design; and,

FIG. 8 is a bottom plan view of the container sleeve showing my new design.

In the drawings, the broken lines depict environmental subject matter only and form no part of the claimed design.
